CLAIM

The ornamental design for an aircraft instrument panel, as shown and described.

DESCRIPTION

FIG. 1 is a perspective view of the aircraft instrument panel showing our new design;

FIG. 2 is a front view of the aircraft instrument panel of FIG. 1;

FIG. 3 is a rear view of the aircraft instrument panel of FIG. 1;

FIG. 4 is a left view of the aircraft instrument panel of FIG. 1;

FIG. 5 is a right view of the aircraft instrument panel of FIG. 1;

FIG. 6 is a top view of the aircraft instrument panel of FIG. 1; and,

FIG. 7 is a bottom view of the aircraft instrument panel of FIG. 1.

In FIGS. 1-7, the broken lines illustrate portions of the aircraft instrument panel that form no part of the claimed design.
